UNITED STATES PATENT OFFICE.

FRITZ BALZER, OF CHICAGO, ILLINOIS, ASSIGNOR TO TROY LAUNDRY MACHINERY COMPANY, LTD., OF CHICAGO, ILLINOIS, A CORPORATION OF NEW YORK.

REVERSING MECHANISM FOR CYLINDER WASHING-MACHINES.

1,376,393.

Specification of Letters Patent.

Patented May 3, 1921.

Application filed June 8, 1916. Serial No. 102,564.

To all whom it may concern:

Be it known that I, FRITZ BALZER, a subject of the Emperor of Germany, residing at Chicago, in the county of Cook and State 5 of Illinois, have invented certain new and useful Improvements in Reversing Mechanism for Cylinder Washing-Machines, of which the following is a specification.

My invention relates, in general, to mechanism 10 for automatically reversing the direction of the moving part of a machine, and more particularly to mechanism for preventing the application of the motive power to drive a motor in a reverse direction until 15 it has come to a stop.

In the operation of various machines it is necessary to periodically reverse the direction of an element, such, for instance, as the cylinder of a washing machine. When 20 the power is applied to drive the moving element in a reverse direction before the element has come to a stop, excessive strain is imposed upon the motor and upon the moving parts whose direction of movement 25 is reversed. For example, in a washing machine in which the cylinder is driven by an electric motor, the current of which is periodically reversed in order to reverse the direction of rotation of the cylinder, the. 30 motor is injured by reversing the current to it while the cylinder continues to rotate in an opposite direction.

One object of my invention is to provide 35 mechanical controlling means for electrically or other power driven machines, which means, when combined with a reversible machine, will control the application of power thereto in a manner to direct the power alternately in opposite directions at 40 the ends of predetermined periods of drive, and through the medium of a power-directing member which is moved alternately to two power-releasing positions through the medium of an actuator that has an initial 45 machine-imparted movement, followed by a self-propelled actuating movement, by which it drives the power-directing member to its new power-releasing position; the power-directing member and its actuator being, 50 however, arrested after the initial movement and prevented from releasing power in the new direction until a machine-driven motion-controlled detent has been permitted to retire by the machine coming to rest.

Another object of my invention is to provide 55 an organization operating as above outlined, in which the actuator will drive the power-directing member to its intermediate or arrested position, and do so by the first 60 part of the actuator's self-propelled movement, so that the arrest of power in one direction, for instance, by opening an electrical circuit, will be effected with a snap.

A still further object of my invention is 65 to provide periodic and automatic reversing mechanism which may be comparatively simple in construction, efficient in operation, and durable in use.

My invention will be more fully disclosed 70 hereinafter with reference to the accompanying drawings in which the same is illustrated as embodied in a convenient and practical form, and in which—

Figure 1 is an elevational view of a cylinder washing machine equipped with my 75 invention;

Fig. 2 an enlarged sectional view through 80 the portion of the casing which incloses the governor, the latter being shown in elevation;

Fig. 3 an enlarged cross-sectional view on line 3—3, Fig. 4;

Fig. 4 a plan view of the reversing mechanism, the top of the inclosing casing being removed;

Fig. 5 a cross-sectional view on line 5—5, Fig. 4;

Fig. 6 a detail view showing the cam actuated circuit controllers;

Fig. 7 a longitudinal section on line 7—7, 90 Fig. 4, and

Fig. 8 a longitudinal sectional view on line 8—8, Fig. 4.

Similar reference characters are used to 95 designate similar parts in the several figures of the drawings.

For purposes of illustration, I have shown 100 and described my invention as applied to a cylinder washing machine, the cylinder of which is rotated alternately in opposite directions by means of an electric motor, the current to which is periodically reversed. My invention, is not, however, limited in its application to any particular machine, but is capable of use in connection with other 105 machines comprising moving elements, the direct movement of which is periodically reversed.

Reference letter A indicates the shell, or casing, of a cylinder washing machine, the ends of which are supported by legs a^1 and a^2 . A¹ indicates the cover of the casing A, which may be opened to permit access to the interior of the casing for the purpose of inserting and removing articles in and from the inclosed cylinder B. B¹ and B² designate the trunnions of the cylinder which project through and are journaled in the heads of the casing A. C designates the usual conduits for supplying water and suds to the casing and for permitting their discharge therefrom. D designates an electric motor suitably mounted upon the washing machine, as by means of a pair of rods D¹ and D², located above the top of the machine and supported at their ends by suitable brackets secured to the heads of the casing. The shaft of the motor D is connected by suitable gearing with one of the trunnions B², of the cylinder, the gearing not being shown in detail as it is inclosed within a suitable housing E.

The washing machine above described does not in itself embody any features of my present invention, and hence need not be more fully described in detail. It is, however, shown in order that the construction and operation of my improved reversing mechanism may be fully understood.

Supported upon the rods D¹ and D², preferably adjacent the opposite end of the cylinder A from the motor D, is a casing F. Any suitable means may be provided for mounting the casing F upon the rods, such for instance, as pairs of brackets f¹ and f² projecting outwardly from the sides of the casing and overlying the said rods D¹ and D². U-bolts f extend around the rods D¹ and D² and project through holes in the said brackets f¹ and f², the upwardly projecting screw-threaded ends of the U-bolts having nuts thereon engaging the upper surfaces of the said brackets. In order to tightly secure the casing F to the supporting rods, clamp screws f³ extend through the brackets into engagement with the said rods as clearly shown in Fig. 3. The casing F is provided with a removable cover F¹, detachably secured thereto by any suitable fastening means, such for instance, as screws F².

Extending longitudinally through the casing F is a shaft G located intermediate of, and parallel to, the rods D¹ and D². The shaft G is connected with the gearing through which the motor D rotates the cylinder B. When the washing machine is of the type having a driving gear wheel secured to both trunnions of the cylinder, the shaft G may be the usual shaft in such machines for connecting the gear wheels at the two ends of the machine. Suitable bearings g¹ and g² surround the portions of the

shaft G which pass through the end walls of the casing F. To provide an actuator for the power-directing member, there is fixed upon the portion of the shaft G within the casing F, a worm G¹ which meshes with the worm-gear H fixed upon a sleeve H¹ extending transversely within the casing F and rotatably supported upon a rod H². One end of the rod H² is supported in a recess formed in a removable bearing h¹ fixed to one side of the casing F. The other end of the rod H² is supported within a sleeve h², projecting inwardly from, and rigidly secured to, the opposite side wall of the casing F.

Loosely supported upon the sleeve H¹ intermediate of the inner end of the sleeve h² and worm-gear H, is a tumbler, in the form of a hub J, having rigidly secured eccentrically thereto a weight J¹ and a camming arm j. Supported upon the bottom of the casing F, immediately below the weight J¹, is a flat spring J², which serves as a yielding support for the weight when it swings downwardly during the operation of the mechanism.

Pivottally supported within the casing F is a yoke K which surrounds and oscillates transversely to the hub J. The bottom of the yoke K is provided at the center thereof with cylindrical bearing upon a stud l, the latter being supported by a lug L¹, projecting upwardly from the bottom wall of the casing F. The inner vertical surfaces of the yoke K are provided with inwardly projecting cams k¹ and k², which are alternately engaged by a cam j carried by the hub J, intermediate of the same and the weight J¹.

Carried by the opposite sides of the yoke K, and projecting outwardly therefrom, are contacts K¹ and K², which are preferably wedge-shaped. Supported within the opposite end walls of the casing F are pairs of contacts M¹ and M², between which the contacts K¹ and K² are alternately forced by the oscillations of the yoke K, in a manner subsequently to be described.

Pins j¹, j² projecting from a face of the worm-wheel H, on opposite sides of the center thereof, are adapted to pick up the radially projecting cam j on hub J and move it until the weight J¹ passes vertical position or completes the initial movement of the actuator and releases said actuator (J, J¹, j) to its self-propelling actuating movement under the force of gravity, by which the cam j moves against one of the cams k¹, k² with ample force to snap the switch contact K¹ K² from between the terminal blades M¹ or M² and present the yoke K, which constitutes the power-directing member, into intermediate position shown in Fig. 7. Here it is arrested by the detent n, which, as herein-after described, is retained in the position of Fig. 7 so long as there is motion in the

driven machine. While the parts are in the position of Fig. 7, cam j , under the influence of the full load of the weight J^1 , is resting against the cam k^2 , ready to complete 5 the throw of the yoke K and close the circuit in the new direction, by introducing contact K^2 between terminals M^2 whenever the detent n is withdrawn.

Pivotedly supported upon the bracket N , 10 suitably supported within the casing F , is a lever N^1 , one end of which rigidly supports a depending detent n , which in one position of the lever N^1 is projected into the path of a stop k projecting upwardly 15 from the center of the yoke K . The lever N^1 is connected by a rod n^1 with one end of a lever O fulcrumed upon a bracket o secured to the end wall of the casing A , as shown in Fig. 2. The opposite end of the 20 lever O , from that to which the rod n^1 is connected, is bifurcated, so as to straddle a ring O^1 mounted to move axially upon the end of the shaft G which projects beyond the casing A . The ends of the bifurcated 25 portion of the lever O , are provided with slots which loosely surround studs o^1 , projecting outwardly from the ring O^1 . Mounted to slide axially upon the portion 30 of the shaft G , adjacent the ring O^1 , is a collar O^2 having radial lugs, to which are pivotally connected pairs of links o^4 , the opposite ends of said links being pivotally connected with weights O^4 , said weights being provided with shanks pivotally connected 35 between pairs of lugs o^3 , upon a collar O^3 fixed upon the end of the shaft G . A spring o^2 surrounds the shaft G , intermediate the fixed collar O^3 and the movable collar O^2 , the tension of which tends to 40 move collar O^2 toward the right in Fig. 2 and thereby oscillate the lever O in a direction to swing the lever N^1 away from the yoke K , and remove the detent n from the path of the stop k on the yoke.

45 The operation of the reversing mechanism above described is as follows:

The motor D rotates the cylinder B , within the casing A through the train of gears interposed between the motor shaft 50 and the trunnion B^2 of the cylinder. The shaft G , which rotates in synchronism with the motor and cylinder, rotates the sleeve H^1 , through the engagement of the worm G^1 with the worm-gear H . Assuming that 55 the worm-gear H is being rotated (see Fig. 8) in clockwise direction a pin j^1 on the worm-gear will be moved into engagement with the radially projecting portion j on the hub J , and the further rotation of the 60 worm-gear will lift the weight J^1 until it reaches a position slightly beyond the vertical, when it will quickly swing by gravity toward the right, and, through the engagement of the cam j with the cam k^2 of the 65 yoke, will oscillate the yoke into the posi-

tion shown in Fig. 7, in which the stop k , through engagement with the detent n , prevents further oscillation of the yoke toward the right. This movement of the yoke has disengaged the contact K^1 carried thereby 70 from the pair of fixed contacts M^1 , thereby interrupting the circuit to the motor. During the rotation of shaft G , the centrifugal action of the governor causes the weights O^4 , through the pairs of links o^4 , to retain 75 the sleeve O^2 in a position to the left of that shown in Fig. 2, so that the lever O is in a position to permit the lever N^1 to swing downwardly into the position shown in Figs. 7 and 8, in which the detent n is 80 in the path of the stop k . When the rotation of the shaft G ceases, by reason of the interruption of the circuit of the motor through the disengagement of the movable contact K^1 from the fixed contacts M^1 , in 85 the manner above explained, the weights O^4 are no longer subjected to centrifugal action, and hence the spring o^2 moves the collar O^2 toward the right (in Fig. 2) and thereby oscillates the lever O and, through 90 the connecting rod n^1 , swings the lever N^1 upwardly so that the detent n is lifted out of the path of the stop k . The weight J^1 is therefore permitted to continue its downward movement by gravity, so that the yoke 95 K is swung toward the right through the contact of the cam j with the cam k^2 . Such further movement of the yoke moves the fixed contact K^2 , carried thereby into engagement with the pair of contacts M^2 , thereby 100 closing a circuit to the motor D to rotate the same in a reverse direction.

After the cylinder has made a predetermined number of rotations, by the coincident rotation of the worm-gear H , in a 105 counterclockwise direction, the pin j^2 (see Fig. 7) is brought into engagement with the projection j on the hub J , and the weight lifted to a position slightly to the left of the vertical, when it falls by gravity 110 until the cam j engages the cam k^1 on the yoke and thereby oscillates the yoke to a position in which the stop k thereon engages the right side of the detent n , when further oscillation of the yoke will be interrupted 115 until the detent has been lifted out of engagement with the stop through the action of the spring o^2 after the shaft J comes to a stop.

From the foregoing description it will be 120 seen that the circuit to the motor cannot be closed to reverse the motor until the cylinder has ceased to rotate. Injury to the motor, and to the movable parts connected therewith, incident to applying power to 125 the motor to rotate the same in one direction before it, and its driven parts, cease to rotate in the other direction is therefore avoided.

In the operation, by a common source of 130

power, of a plurality of machines, each comprising a movable member the direction of movement of which is periodically reversed, such for instance, as cylinder washing machines, it is desirable that the reversing of no two of the machines should occur simultaneously, inasmuch as the starting of the movable members requires a maximum consumption of power, and obviously for economical reasons, the periods of such maximum consumption of power should occur serially, and not simultaneously in the several machines. In my Letters Patent No. 1,238,082, issued August 28, 1917, I have disclosed a system for controlling electrically driven washing machines in which the cylinders are periodically reversed in succession, the reversal of the motor of each machine being controlled by all of the other machines, so that no two machines can reverse simultaneously. When my present invention is applied to a cylinder washing machine which forms one of a group of such machines, all driven by the same source of power, it is desirable that circuit controlling means should be provided at each machine for governing the reversing of the other machines in the group so that no two machines may reverse at the same time. I accomplish this by adding to the reversing mechanism hereinbefore described in detail, automatically operated auxiliary circuit controllers, for controlling the circuits which reverse the motors of the other machines.

Splined upon the sleeve J at the left of the worm-gear H (see Fig. 5) is a sleeve P. Surrounding and secured to the sleeve P, are rings p^1 , p^2 , p^3 , and p^4 , each of which is provided with a radially projecting cam. Loosely surrounding the sleeve P is a ring p , preferably located intermediate of two of the cam rings in order to be longitudinally immovable upon the sleeve P. Projecting radially from opposite sides of the ring p are studs P^1 and P^2 , which are surrounded by slots formed in the ends of levers Q^1 and Q^2 , respectively. The levers Q^1 and Q^2 are fulcrumed upon brackets q^1 and q^2 , secured within the end walls of the casing F. Pivotedly supported upon the bottom of the casing F, beneath the lever Q^1 , is a bell-crank lever R^1 provided with an inwardly projecting end terminating in the path of the yoke K. The opposite end of the bell-crank lever R^1 is provided with an upwardly projecting pin r^1 , which engages within a slot in the lever Q^1 . Pivotedly mounted upon the bottom of the casing F, below the lever Q^2 , is a bell-crank lever R^2 , one leg of which terminates in the path of the yoke K, while the shorter leg thereto carries an upwardly projecting stud r^2 , which engages a slot in the lever Q^2 .

Pivotedly supported within the casing F, as by means of a rod S projecting inwardly

therefrom (see Figs. 3 and 8), are two short levers S^1 and S^2 , each of which is provided with an anti-friction roller resting upon a corresponding one of the underlying cam rings on the sleeve P. The levers S^1 and S^2 have secured to their ends upwardly projecting contacts s^1 and s^2 , over which are supported fixed contacts t^1 and t^2 . The contacts t^1 and t^2 , may be supported within the casing in any suitable manner, as by means of an extension on the bracket N. The contacts s^1 and t^1 coöperate to control an auxiliary circuit, such, for instance, as that of the motor of another machine, while contacts s^2 and t^2 control a second auxiliary circuit, such, for instance, as that of the motor of still another machine.

The sleeve P rotates in synchronism with the rotation of the worm-gear H, and as it rotates the cam on the ring p^1 is moved beneath the roller on the lever S^1 , thereby oscillating the same upwardly and lifting the contact s^1 into engagement with the contact t^1 . The rotation of the sleeve P also causes the cam on the ring p^2 to engage the roller of the lever S^2 , and lift the same so as to raise the contact s^2 into engagement with the contact t^2 . The cams on the rings p^1 and p^2 are so related to each other, and also to the pin j^1 on the worm-gear H, that contact is not made between the contacts s^1 and t^1 , or the contacts s^2 and t^2 , or the contacts K^2 and M^2 , at the same time. Consequently the circuits of no two of the motors of the machines in the group are closed at the same time.

Where the machine is one of a group of three in order that the circuits of the motors of the other machines may be closed in proper sequence, it is necessary that when the direction of rotation of the sleeve P is reversed upon the reversing of the shaft G, other cams should be brought into coöperative relation with the levers S^1 and S^2 , in order that they may be actuated in proper sequence to secure the predetermined reversing of the machines in the circuits of which they are located. This is accomplished by providing the second pair of cam rings p^3 and p^4 , the cams on which are so located that when the rotation of the sleeve P is reversed they will be brought beneath the levers S^1 and S^2 , and lift them in the same sequence that they were lifted by the cams on the rings p^1 and p^2 , when the sleeve P was rotating in the first direction. The shifting of the cam rings relatively to the levers S^1 and S^2 upon the reversal of the direction of movement of the yoke K is effected by means of the yoke alternately engaging levers R^1 and R^2 . When the yoke oscillates to the left in Fig. 8, it engages the end of the lever R^1 and oscillates the same in a direction to swing the lever Q^1 toward the worm-gear H, thereby moving the cam

rings p^1 and p^2 beneath the levers S^1 and S^2 . When the yoke is oscillated to the right in Fig. 8, it engages the lever R^2 and oscillates the same, so as to swing the lever Q^2 away 5 from the worm-gear H , and thereby so shift the sleeve P as to move the cam rings p^3 and p^4 beneath the levers S^1 and S^2 .

It will, of course, be evident that any number of auxiliary circuits may be controlled 10 by merely providing additional pairs of contacts similar to s^1 and t^1 , and s^2 and t^2 , and providing additional pairs of cam rings on the sleeve P . It will be further evident that if the machine is to control, and be controlled 15 by the reversing of only one other machine, it is unnecessary to provide more than one cam for closing the auxiliary circuit.

Inasmuch as my invention resides in the reversing mechanism and not in the circuits, 20 or in the reversing switches, I have deemed it unnecessary to illustrate and describe the circuits of the motor D , or of other motors of other machines which may be controlled by the auxiliary controllers. In my said co- 25 pending application, Serial No. 27,660, I have illustrated and described in detail, an arrangement of circuits and reversing switches for a plurality of inter-controlling motors, but in order that my present invention may be fully disclosed, it is not necessary 30 that the circuits and reversing switches should be illustrated or described.

While I have described my invention with more or less minuteness and as being embodied in certain precise forms, yet it will be understood that I do not limit myself thereto unduly, or any more than is pointed out in the claims; on the contrary, I contemplate all proper changes in form, construction, and 40 arrangement, the omission of immaterial parts, and the substitution of equivalents, as circumstances may suggest or necessity render expedient.

I claim:

45 1. In a mechanism for reversing the drive of a power actuated machine, a power-directing member movable alternately to two power-releasing positions, an actuator moving in opposite directions for driving said power-directing member and having, in each direction, a machine-imparted initial movement and a self-propelled actuating movement from the end of said initial movement, and a machine-motion-controlled stop, arresting 50 the power-directing member and the actuator after the former has reached an intermediate position and after the latter has completed its initial movement.

2. In a mechanism for reversing the drive 60 of a power actuated machine, a power-directing member movable alternately to two power-releasing positions, an actuator moving in opposite directions for driving said power-directing member and having, in each direction, a machine-imparted initial move-

ment and a self-propelled actuating movement from the end of said initial movement, and a machine-motion-controlled stop, arresting the power-directing member and the actuator after the former has reached an 70 intermediate position and after the latter has completed its initial movement; said actuator being arranged to move the power-releasing member to said intermediate position. 75

3. In a mechanism for reversing the drive of a power actuated machine, a power-directing member movable alternately to two power-releasing positions, an actuator moving in opposite directions for driving said 80 power-directing member and having, in each direction, a machine-imparted initial movement and a self-propelled actuating movement from the end of said initial movement, and a machine-motion-controlled stop, arresting the power-directing member and the actuator after the former has reached an intermediate position and after the latter has completed its initial movement; said actuator being arranged to move the power-releasing member to said intermediate position by the first part of its self-propelled movement. 85

4. In a mechanism for reversing the drive of a power actuated machine, a power-directing member movable alternately to two power-releasing positions, an actuator moving in opposite directions for driving said power-directing member and having, in each direction, a machine-imparted initial movement and a self-propelled actuating movement from the end of said initial movement, and a machine-motion-controlled stop, arresting the power-directing member and the actuator after the former has reached an 100 intermediate position and after the latter has completed its initial movement; said actuator comprising a weighted lever developing its self-propelled movement by gravitation and arranged to move the power-releasing member to intermediate position by the first part 105 of its gravitating movement and remaining suspended in opposition to gravity when arrested by the detent. 110

5. In a mechanism for reversing the drive 115 of a power actuated machine, a power-directing member movable alternately to two power-releasing positions, an actuator moving in opposite directions for driving said power-directing member and having, in each 120 direction, a machine-imparted initial movement and a self-propelled actuating movement from the end of said initial movement, and a machine-motion-controlled stop arresting the power-directing member and the 125 actuator after the former has reached an intermediate position and after the latter has completed its initial movement; said power-releasing member comprising an oscillating yoke having cams through which 130

to move it in opposite directions, and said actuator comprising a lever acting against said cams.

6. In a mechanism for reversing the drive of a power actuated machine, a power-directing member movable alternately to two power-releasing positions, an actuator moving in opposite directions for driving said power-directing member and having, in each direction, a machine-imparted initial movement and a self-propelled actuating movement from the end of said initial movement, and a machine-motion-controlled stop, arresting the power-directing member and the actuator after the former has reached an intermediate position and after the latter has completed its initial movement; said power-releasing member comprising an oscillating yoke having cams, and said actuator comprising a swinging lever having a radially offset weight which induces the self-propelling movement of the actuator, and an arm through which it acts against said cams.

7. In a mechanism for reversing the drive of a power actuated machine, a power-directing member movable alternately to two power-releasing positions, an actuator moving in opposite directions for driving said power-directing member and having, in each direction, a machine-imparted initial movement and a self-propelled actuating movement from the end of said initial movement, and a machine-motion-controlled stop, arresting the power-directing member and the actuator after the former has reached an intermediate position and after the latter has completed its initial movement; said power-releasing member comprising a yoke pivoted at one end of its vertical axis and having its intermediate arresting position approximately in equilibrium upon its pivot and its power-releasing positions on opposite sides of said position of equilibrium.

8. In a mechanism for reversing the drive of a power actuated machine, a power-directing member movable alternately to two power releasing positions, an actuator moving in opposite directions for driving said power-directing member and having, in each direction, a machine-imparted initial movement and a self-propelled actuating movement from the end of said initial movement, and a machine-motion-controlled stop, arresting the power-directing member and the actuator after the former has reached an intermediate position and after the latter has completed its initial movement; said power-releasing member comprising a yoke pivoted at one end of its vertical axis and having its intermediate arresting position approximately in equilibrium upon its pivot and its power-releasing positions on opposite sides of said position of equilibrium, and said actuator comprising a lever swing-

ing upon a fulcrum above the path of the yoke and acting against opposite sides of the yoke through the medium of cams.

9. In a mechanism for reversing the drive of a plurality of power actuated machines, a power-directing member movable alternately to two positions in which it releases power in opposite directions to one of the machines, an actuator moving in opposite directions for driving said power-directing member and having in each direction a machine-imparted initial movement and a self-propelled actuating movement from the end of said initial movement, and a machine-motion-controlled stop, arresting the power-directing member and the actuator after the former has reached a position intermediate of its power-releasing positions and after the latter has assumed self-propelling position, and an independent power-releasing member for a second machine, comprising a lever and cam connection between said lever and the actuator, positioned to actuate said lever to affect the second machine before the first-named power-directing member reaches power-releasing position.

10. The combination with a machine comprising a moving member, of an electric motor connected to said member, a circuit controller for reversing the circuit to said motor, means actuated by a predetermined movement of said member for effecting a reversing movement of said controller, and means controlled by said moving member for retaining said controller in an inoperative position until said member ceases to move.

11. The combination with a machine comprising a moving member, of an electric motor connected to said member, a controller for reversing the circuit to said motor, means actuated by a predetermined movement of said member for effecting a reversing of said controller, means controlled by said moving member for arresting the throw of said controller in an inoperative position until said member ceases to move, and a controller for a second circuit actuated by said means in predetermined relation to said first controller.

12. The combination with a machine comprising a moving member, of an electric motor connected to said member, a circuit controller for reversing the circuit to said motor, means actuated by a predetermined movement of said member for effecting a reversing movement of said controller, mechanism operable by said movable member for arresting the throw of said controller in an inoperative position until said member ceases to move, circuit controllers for other circuits than that of said motor comprising fixed and movable contacts, cams actuated by said means for closing the contacts of said controllers in predetermined

relation, and means for shifting different cams into operative relation to said movable contacts when the circuit to said motor is reversed.

5 13. The combination with a machine comprising a moving member, of an electric motor connected to said member, a controller for reversing the circuit to said motor, a weight actuated by a predetermined movement of said member for effecting a reversing movement of said controller, a stop for arresting the throw of said controller in an inoperative position, and a centrifugal governor operated by said member and connected with said stop for moving the same out of engagement with said controller only when said member has substantially ceased to move.

10 14. The combination with a machine comprising a moving member, of an electric motor connected to said member, a controller for reversing the circuit to said motor, a weight actuated by a predetermined movement of said member for effecting a reversing movement of said controller, a stop for arresting the throw of said controller in an inoperative position, means for maintaining said controller against said stop, and means for moving said stop out of engagement with said controller only when said member has substantially ceased to move.

15 15. The combination with a machine comprising a moving member, of an electric motor connected to said member, a controller for reversing the circuit to said motor, a weight actuated by a predetermined movement of said member for effecting a reversing movement of said controller, a stop for arresting the throw of said controller in an inoperative position, and means operated by said member and connected with said stop for moving said stop out of engagement with said controller only when said member has substantially ceased to move.

20 16. In a power-controlling mechanism for a plurality of reversible machines, a power-directing member for one machine adapted to assume, alternately, two power-releasing

positions for the first machine, an actuator for said power-directing member, a detent 50 arresting said power-directing member and actuator in intermediate position, a second power-releasing member for a second machine, and cam controlling means interposed between said actuator and said second power-directing member; said cam controlling means comprising a plurality of cams movable alternately into controlling relation with the second power-directing member, and each adapted to time the operation 60 of the second power-directing member in particular relation to one of the movements of the first power-directing member, and means for shifting said cams to and from operative relation to the second power-directing member.

25 17. In a power-controlling mechanism for a plurality of reversible machines, a power-directing member for one machine adapted to assume, alternately, two power-releasing 70 positions for the first machine, an actuator for said power-directing member, a detent arresting said power-directing member and actuator in intermediate position, a second power-releasing member for a second machine, and cam controlling means interposed between said actuator and said second power-directing member; said cam controlling means comprising a plurality of cams movable alternately into controlling relation 80 with the second power-directing member, and each adapted to time the operation of the second power-directing member in particular relation to one of the movements of the first power-directing member, and means 85 for shifting said cams to and from operative relation to the second power-directing member, comprising a lever system controlled by the first power-directing member.

30 In testimony whereof, I have subscribed 90 my name

FRITZ BALZER.
